DESIGN FOR A BOTTLE

William Knox, Burlington, Vt.

Application December 3, 1936, Serial No. 66,295

Term of patent 14 years

To all whom it may concern:

Be it known that I, William Knox, a citizen of the United States and a resident of Burlington, county of Crittenden, and State of Vermont, have invented a new, original, and ornamental Design for a Bottle, of which the following is a specification, reference being had to the accompanying drawing, forming a part thereof.

In the drawing:

I claim:

The ornamental design for a bottle, substantially as shown.

WILLIAM KNOX.
